UNITED STATES PATENT OFFICE

2,471,113

SPORTS SHOE

Frank A. Melchionna, Cincinnati, Ohio

Application September 29, 1947, Serial No. 776,840

15 Claims. (Cl. 36—2.5)

1

The present invention relates to spiked shoes for various outdoor sports and has for an object the provision of a spike mounting assembly that is easier and less expensive to apply to the shoe and which provides a sturdier and more comfortable finished sports shoe.

Another object of the invention is to provide a spike or cleat receiving structure for shoes that is arranged so as to minimize the opportunity for water to pass alongside the spike receiving member to the inside of the shoe.

Still another object of the invention is to provide spike mounting devices that can be salvaged from a pair of worn out or badly damaged shoes if desired and installed in a different pair of shoes in one of several different ways.

A further object of the invention is to provide a spike or cleat mounting assembly wherein the means for receiving the replaceable spikes cannot work loose and thus make it practically impossible to replace a worn spike.

These and other important objects are attained by the means described herein and shown in the accompanying drawings in which:

Fig. 1 is a fragmental side elevational view of a football shoe embodying the invention, part being shown in section.

Fig. 2 is a sectional view taken on line 2—2 of Fig. 1, the sock liner being removed and the insole being partly broken away.

Fig. 3 is an enlarged sectional view taken on line 3—3 of Fig. 2.

Fig. 4 is a sectional view taken on line 4—4 of Fig. 1.

Fig. 5 is a fragmental top plan view of a golf shoe structure embodying the plate of the invention having threaded socket members fixed therewith, the sock liner being removed and the insole partly broken away.

Fig. 6 is a cross-sectional view taken on line 6—6 of Fig. 5.

Fig. 7 is a view similar to Fig. 6 but showing a track shoe spike in place of the golf shoe spike.

Fig. 8 is a fragmental cross-sectional view showing the details of a modified form of spike plate as applied to an existing shoe and covered by an applied half sole.

According to present practice cleats or spikes for golf shoes, track shoes, football shoes and the like are individually mounted with complementary threaded members applied through concentric holes in the insole and outer sole of the shoe and an intermediate perforated metal plate. The procedure is somewhat expensive and it often happens that the metal plate in the shoe or the

2

threaded mounting member or both become loose and rusted. Mounting members when loose are uncomfortable for the wearer of the shoe since only the sock liner of the shoe covers the heads of the mounting members in most of these shoes. The mounting members when loose permit water to seep inside the shoe and the supposedly removable spike becomes rusted to the loose mounting member so that the rusted parts turn as a unit relative to the plate thus making it impossible to remove the spike from the shoe for replacement of the spike or tightening of the loose parts without tearing the shoe apart.

According to the present invention I permanently fix on the metal reenforcing plate the several threaded stud members, or socket members, or the spikes and thus provide a unitary member that is easier to build into the new shoe and which can be salvaged from worn out shoes if desired and applied in several other fashions to existing shoes which are thereby converted into extra pairs of sports shoes for the same or other persons. At the same time the unit, however used is more comfortable to the foot of the wearer and the tendency to water seepage to the inside of the shoe is substantially eliminated. All of the previously mentioned disadvantages are eliminated.

Referring to the drawings, Figs. 1, 2, 3 and 4 are illustrative of the invention as built into a new football shoe 10 wherein the insole 11 is imperforate and has the usual sock liner (not shown) applied in customary manner. Interposed between the insole 11 and the outer sole 12 are suitable metal reenforcing plates 13 having a plurality of tack receiving holes such as 14 adjacent its edges for passing the tacks or nails 15 whereby the unit is secured to the inside or top face 16 of outer sole 12. The plate 13 has a plurality of threaded studs 17 rigidly fixed thereon, arranged according to approved pattern, and extending from one face thereof so that they may pass snugly through holes 18 that are punched through the outer sole 12, and threadedly receive the replaceable truncated conical cleats or spikes 19 usually applied to football shoes. The usual externally applied washer (not shown) may be omitted between the outside of the sole 12 and the base of cleat 19, or it may be used if desired.

I prefer to assemble the plate unit comprising the sheet metal plate 13 and the studs in the following manner to assure a strong, permanent mounting of the parts that will afford a flat imperforate surface on the plate portion of the finished unit for seating against the bottom

surface of a continuous, imperforate insole such as 11, or on any shoe sole. The plate 13 is initially formed with circular flat bottomed bosses 20, the annular wall 21 of each of which is sufficient in height to allow the flat top of head 22 on the stud 17 to seat in flush relation with the surface of the plate. As can be best seen in Fig. 4 the boss has an approximately square hole 23 formed therethrough, and an initially enlarged cylindrical portion of the stud adjacent the head 22 is passed through the square hole 23 in plate 13 and swaged to fill said hole snugly as at 24 and to form a thin annular collar or rivet shoulder 25 that overhangs and tightly clamps on the outside face of the boss beyond the edges of said square hole 23. The stud 17 is thus fixed against movement in the plate. There is no likelihood of the stud loosening in the plate. Hence the removable spike or cleat can always be removed when replacement is required. Spot welds or any other additional fastening (not shown) may be resorted to for imparting further security to the mounting of the studs on the plate.

The plate unit with the studs attached is quickly and easily built into the shoe. The unit is merely placed in position on the top face of the outer sole and struck with a hammer so that the ends of the studs serve as template to mark the locations where holes 18 are to be punched. Thereafter the studs are forced through said holes and nails 15 are driven through the marginal holes 14. The completion of the shoe is then followed through in approved manner.

A heel plate 130 properly shaped and carrying a desired number of spike or cleat mounting studs is constructed and installed in the shoe structure in a similar manner as will be readily understood without further explanation.

The plate unit just described may be applied to an existing shoe by merely securing it to the exposed bottom face of the outer shoe sole by suitable clinch nails passing through holes 14 into the outer sole. The studs 17 receive the removable football or other socket type spikes and are screwed against the exposed face of the plate, fully covering the boss on the plate. This will suffice for use by the younger players. If desired a half sole may be perforated to pass the studs and may be seated over the plate with a sewed or nailed fastening to the outer sole applied in known manner by any shoe repair shop. The spikes are then screwed onto the studs.

In Fig. 8 there is shown a modified structure wherein the studs 170 are secured to the plate 13 in the previously described manner but the free end of the stud is fashioned to form the spike for a golf or track shoe. The one piece arrangement can be applied to the outer sole in either an exposed or concealed relation. If the plate unit is to be exposed the mere attachment to the outside face of the outer sole 12 completes the attachment and the shoe plate is ready for use. However in this embodiment of the invention several cleat threads 26 are formed at the base of the spike 170 adjacent boss 20 on the plate so that a half sole 27 may be passed over the spikes and sealed around the spikes by flanged nuts 28 screwed onto the threads 26. A less expensive type of sports shoe may also be made by building the one piece structure as just described into the shoe between the insole and outer sole. It will be understood that the spikes are not removable in such a shoe, and that the plate unit must be replaced when the spikes are badly worn.

The plate units are also provided in modified form with threaded socket members thereon for receiving cleats or spikes that have threaded studs fixed to or integral therewith, for example as used for golf shoes and track shoes.

In this embodiment the plate 29 has a selected number of downwardly pressed bosses 30 suitably located and formed similarly to the bosses 20 in plate 13. A square hole 31 in each boss serves to pass the initially cylindrical exterior body of an internally threaded socket member 32 when the flange or head 33 thereof is entered into the hollow interior of the boss 30, flush with the top surface of plate 29. The body is swaged to fill the square hole 31 and to overlap the edges of the hole on the outside of the boss at 34 thereby fixing the threaded socket member permanently to the plate and also positively preventing the socket member from turning in the plate. The modified form of a plate unit embodying the internally threaded socket members permanently fixed thereto according to approved patterns for golf shoes serve as marking templates for locating the centers for punched holes 35 in the outer sole 36 of a golf shoe in which the plate is to be installed following the procedure explained in connection with the football shoe of Figs. 1 to 4. Thereafter the threaded shank 37 of a removable or replaceable golf spike 38 is passed threadedly through the hole 35 in the sole and into the threaded bore in the socket member until the flange 39 of the spike seats solidly on the face of the sole. A washer (not shown) may be interposed between the sole and said flange 39 if desired.

As will be seen in Fig. 6 the insole 40 is imperforate and it seats on the flat smooth top face of the plate 29 and affords enhanced comfort to the wearer of the shoe.

The socket carrying plate 29 with a properly arranged series of sockets for the spikes of a track shoe wherein, as shown in Fig. 7, the outer sole 40 and insole 41 of proper thickness will have plate 29 mounted between them in the manner previously explained. The track spikes 42 are removably mounted in substantially the same fashion as in the golf shoe.

In all its embodiments the cleat or spike installation of the invention in shoes affords easier and less expensive initial effort and it provides the greater comfort of an imperforate insole resting on a flat continuous surface of the metal plate. The shoes so equipped are characteristically less likely to become wet inside and uncomfortable on the foot of the wearer when used in wet weather and they do not deteriorate as rapidly as the previously known spiked and cleated shoes.

In all cases the ability to remove the replaceable type spikes or cleats is assured and there is no need of discarding an otherwise serviceable shoe because the threaded receiving member in the shoe turns with the worn cleat or spike when trying to unscrew it for replacement. Very few shoe repairmen or rebuilders are qualified to rebuild sports shoes with new spike or cleat mountings of the currently known and used type, and the procedure is very expensive. This disadvantage is completely eliminated by the present invention in all embodiments and a very desirable sports shoe is produced at lesser cost using any of the arrangements described herein. The necessary spike or cleat replacements can always be made with certainty by the user if desired and the application of the one piece ar-

rangements on the outside of a shoe can be accomplished by practically any shoe repairman.

What is claimed is:

1. In a spike mounting plate for a sports shoe, a sheet metal plate adapted marginally for attachment to a selected face of an outer sole of a shoe, said plate having shallow bosses formed in predetermined relation and forming depressions in the top of the plate, said depressions each having a noncircular hole therethrough, spike elements comprising flat head portions seating in the depressions flush with the top surface of the plate and a threaded shank portion accessible from the bottom of the plate, said shank portions being swaged immediately below the head to form a noncircular portion conforming to and binding on the edge of the corresponding hole in said plate and conforming to and binding on a marginal surface of the boss surrounding the hole said elements are permanently and immovably fixed to the bosses.

2. In a spike mounting plate for a sports shoe, a sheet metal plate adapted marginally for attachment to a selected face of an outer sole of a shoe, said plate having shallow bosses formed in predetermined relation and forming depressions in the top of the plate, said depressions each having a noncircular hole therethrough, spike elements comprising flat head portions seating in the depressions flush with the top surface of the plate and a threaded shank portion accessible from the bottom of the plate, said shank portions being swaged immediately below the head to form a noncircular portion conforming to and binding on the edge of the corresponding hole in said plate and conforming to and binding on a marginal surface of the boss surrounding the hole said elements are permanently and immovably fixed to the bosses, the threaded shank portions adapted for the reception of complementarily threaded removable spike members.

3. In a spike mounting for sports shoes the combination of a flat metal plate adapted marginally for attachment to a shoe sole member, a removable spike member, a complementary spike element swaged into the body of the plate flush with the top of the plate and cooperating means on the spike member and spike element for connecting the spike member to the spike element.

4. A spike mounting for a sports shoe comprising a flat metal plate for mounting on an outer sole, threaded spike receiving elements including flat flanged head portions flush with the top of the plate and an integral noncircular swaged portion passing through the plate and binding on the faces of the plate supporting said head and complementarily threaded spike members for removable connection with said spike elements.

5. In a device of the class described a thin sheet metal plate having a flat top with shallow depressions, headed spike elements seated in said depressions flush with the flat top surface of the plate, said elements having thread carrying shank portions at the end thereof and having noncircular portions passing through and permanently swaged into edge binding relation with the body of the depression and on to the bottom of the depressions and removable spike members having complementary threads for connecting them to the respective shank portions.

6. In a sports shoe the combination of an outer sole member, a superposed imperforate insole member secured thereto, and a thin sheet metal plate having a flat continuous upper face disposed flatwise against the bottom of one of said

sole members and fixedly secured on the outer-sole member, said metal plate having threaded spike elements swaged nonrotatably and integrally therewith and adapted for the reception of complementary threaded spike members.

7. In a spiked sports shoe the combination of an outer sole member having perforations therethrough, a sheet metal plate on said sole member, integrally and non-rotatable swaged spike elements on said plate provided with threaded portions in registry with the perforations in said sole member, an imperforate insole superposed on the outer-sole member above said plate and a complementary threaded member removably attached to each of said threaded portions and engaging the outer sole member around one of the perforations.

8. A sports shoe comprising an imperforate insole member, an outer sole member, a noncircularly perforated sheet metal plate, integrally swaged spike elements in said perforations and means securing said plate to the outer sole, said plate having a flat continuous and impervious top face seating on the bottom of one of said sole members.

9. A sports shoe comprising an outer sole member perforated in predetermined pattern for the location of spikes, a sheet metal plate including integrally, and swagedly connected spike elements therein having threaded portions in registry with the perforations in said outer sole member and complementary threaded spike members removably connected to the threaded portions of said spike elements for pressing the outer sole to said plate around said perforations.

10. In a sports shoe an imperforate insole, a flat topped substantially imperforate metal plate supporting a major area of said insole, an outer sole supporting said plate and marginally secured to the insole, means securing said plate marginally to said outer sole, integral spike elements on said plate and passing through said outer sole, said spike elements each including a threaded portion, and complementary threaded members connected with the spike elements for sealing the outer sole to said plate around said spike elements.

11. In a sports shoe, an outer sole member having a perforation therethrough, a thin sheet metal plate secured to the top face of said sole member, an internally threaded spike element swaged integrally to the plate in registry with the perforation in the sole member and a removable spike member having a threaded end engageable in the threaded spike element and adapted to engage the outer face of the outer sole surrounding said perforation.

12. In a sports shoe, an outer sole member having a perforation therethrough, a metal plate secured on the top face of said outer sole member, said plate having a downwardly extending shallow boss, a spike element countersunk in the top face of the plate and integrally connected thereto, said element including an externally threaded member passing through the boss and the perforation in said outer sole member, and an internally threaded member removably screwed on said spike element into contact with the sole member surrounding the perforation.

13. In a sports shoe, an outer sole member, a spike plate and an imperforate insole secured in superposed relation, said plate having an integrally connected spike element, said spike element including an externally threaded portion passing through the outer sole, and means threadedly engaging said threaded portion for sealing

the sole against the plate around the spike element.

14. In a sports shoe the combination of an imperforate outer sole and an imperforate superposed insole, a metal plate secured to the bottom of said outer sole, said plate having a hollow boss, a headed spike element fixed integrally to said boss and having an exposed threaded portion below said plate, a half-sole perforated for the passage of the spike element and secured to the outer sole and covering the plate, and a nut threaded onto the spike element and engaging said half-sole around the spike element.

15. In a device of the class described a sheet metal plate having non-circular perforations, spike mounting elements comprising thin heads seating on one face of the plate surrounding the perforations and integral thread carrying portions passing through the perforations beyond the opposite face of the plate and a swaged portion on said elements immovably fixing the elements to both faces of the plate, into the non-

circular edges of the perforations the plate having at least one face adapted for flatwise seating relation with a shoe sole element.
